UNITED STATES PATENT OFFICE.

ALMERON M. LANE, OF MERIDEN, CONNECTICUT.

CLOCK-CASE.

SPECIFICATION forming part of Letters Patent No. 684,575, dated October 15, 1901.

Application filed March 2, 1901. Serial No. 49,562. (No model.)

To all whom it may concern:

Be it known that I, ALMERON M. LANE, a citizen of the United States, residing at Meriden, in the county of New Haven and State 5 of Connecticut, have invented new and useful Improvements in Mattings and Dials for Clock-Cases, of which the following is a specification.

My invention relates to improvements in 10 mattings and dials for clock-cases; and the objects of my improvement are economy in construction and efficiency of the article.

In the accompanying drawings, Figure 1 is 15 a sectional view of the clock-case body, together with the glass and matting, and a plan view of the clock-case back, the movement-frame, and the dial supported on the said frame. Fig. 2 is a detached rear elevation of the dial. Fig. 3 is a detached rear elevation of the matting. Fig. 4 is a side elevation or edge view of the said matting. Fig. 5 is an enlarged rear elevation of a portion of the said matting. Fig. 6 is a sectional view of a portion of the front part of the clock- 25 case, and Fig. 7 is a sectional view of a portion of my matting and its glass with a modified form of clock-case.

A designates the sides or body of my clock-case, the same being illustrated in Figs. 1 and 30 6 as having a separately-formed glass-retaining ring 8 and shoulder 9, the body of the said ring 8 being cylindrical and extended inside of the case-body A at its front and permanently secured thereto in any ordinary 35 manner--as, for example, by indentations 10 from the inside, as shown in Fig. 6. In this connection I may say that it is common to form the glass-holding shoulder integral with the case-body, as shown at 8^a, Fig. 7, for the 40 case-body A', and my matting is applicable to either form of case. It is also common to form a ring substantially like the ring 8 with a glass-holding shoulder at the front edge of the short cylindrical portion of the said ring, 45 the same being hinged or otherwise secured in place, so as to form the sash of a clock-case, and my invention is equally applicable to said sash, which is so well known as to require no illustration nor special description. 50 My matting 11 is mainly of an ordinary form. It is struck up from a disk of metal and the central portion removed, so as to leave it in

the ordinary form of a beveled ring with a flange 12 at its edge. I make L-shaped cuts in the said flange and bend back the metal 55 therefrom to form the rearwardly-projecting lugs 13, the said lugs being bent on nearly radial lines and so as to slant outwardly a little beyond the edge of the flange 12, as shown, whereby the diameter of the circle described 60 by the series of lugs at their rear or outer ends is somewhat in excess of the diameter of the flange 12. The diameter of the flange and that of the cylindrical portion into which it is placed are so proportioned to each other 65 that the flange will easily enter and substantially fill the said cylindrical portion. The usual glass 14 is inserted in the sash, ring, or clock-case body in the rear of the holding-shoulder, and the matting is then crowded or 70 forced into the cylindrical portion adjacent to the said shoulder until the glass is held tightly between the said shoulder and matting. In thus being forced into place the lugs by contact with the ring are bent inwardly a 75 little to bring them under tension, so that they bear with all the resiliency of the metal against the inner wall of the short cylindrical portion into which they are forced and firmly hold the matting in place by friction. 80 It should be noted that while forcing the matting into place has a tendency to bend the lugs toward the center of the matting, so that the said matting is easily pushed into place, the reverse is true when an attempt is made 85 to withdraw the matting, and rearward pressure on the glass only tends to bind the lugs more tightly against the surrounding cylindrical portion within which they are placed. Heretofore it has been customary to discard 90 the metal cut from the center of the matting as so much scrap; but by a novel construction of the dial I am enabled to utilize this heretofore waste center. As in most dials now in use, my dial consists of a metal back 95 and a front face or veneer of paper or other suitable material. It differs from the common dial in that I form the metal back 15 of a smaller diameter than that of its face 16. My combined dial and matting also differs 100 from those in common use in that I make the face 16 of a larger diameter than the opening 17 in the center of the matting, while the metal back 15 is of the same diameter as the

said opening 17, and, further, I form these backs of the identical pieces of metal that are cut from the center of the mattings.

All clocks that employ a dial and a matting have means of some kind for holding the matting concentrically over the dial, and in the same sense means of some kind for this purpose is essential to my invention. The particular means therefor which I have selected for illustration is as follows: In the metal back 15 I cut out four legs 18 at right angles thereto, and I secure the dial to the front movement-plate 19 by means of the said legs. The movement-plates 19 and 20 are connected by posts 21 to the clock-case back 22, which is received in and secured to the sides or body A of the case, all as in any known or ordinary clock, whereby the dial and matting are held in proper relations to each other through the movement-frame and the case-body. The particular kind of means for thus holding the dial and matting in proper relations to each other is not essential to my invention. By my improvements I effect a great saving of metal by making the dial-back smaller than its face and small enough so that the metal cut from the center of the matting is large enough for the metal back. The said back properly supports the face at all points that are liable to ever receive any pressure in the ordinary use of the clock. My improved matting is cheaply con-

structed, holds the glass firmly against rattling, and at the same time is not liable to so bind the glass as to break it.

35

I claim as my invention—

1. The herein-described matting for clock-dials having the flange with the series of lugs formed thereon and bent rearwardly therefrom with the lines of bend extending inwardly in a transverse direction to the edge of the said flange for frictionally holding the said matting against the glass within a surrounding cylindrical member substantially as described.

40

2. A clock-dial consisting of a metal back and a front face secured thereto, the said face being of a larger diameter than the said back and projecting beyond the edges thereof substantially as described.

45

3. The combination of the dial-matting with a clock-dial consisting of a metal back and a front face secured thereto, the said face being of a larger diameter than the said back, and the said back being of substantially the same diameter as the diameter of the said matting, whereby the said back may be cut out from the said matting, substantially as described.
